UNITED STATES PATENT OFFICE.

JOHN E. HOWE, OF NEW YORK, N. Y.; FLORENCE D. HOWE ADMINISTRATRIX OF SAID
JOHN E. HOWE, DECEASED.

INSULATING-BLOCK FOR BUILDING PURPOSES.

1,172,710.

Specification of Letters Patent.

Patented Feb. 22, 1916.

Application filed May 9, 1908. Serial No. 431,955.

To all whom it may concern:

Be it known that I, JOHN E. HOWE, a citizen of the United States, and resident of the borough of Manhattan, city, county, and State of New York, have invented certain new and useful Improvements in Insulating-Blocks for Building Purposes, of which the following is a specification accompanied by drawings.

10 This invention relates to improvements in insulating blocks for building purposes, and the objects of the invention are to improve upon the construction of such blocks and increase the effectiveness of their insulation as 15 regards the transmission of heat, cold and sound. These blocks or unit elements are particularly adapted for use in partitions, ceilings or floors, although they may be used wherever found applicable, as for instance, 20 for boiler and duct coverings, pipe coverings and for insulating linings.

Further objects of the invention will hereinafter appear and the invention consists of the insulating block or unit elements substantially as hereinafter fully described and claimed in this specification and shown in the accompanying drawings, in which—

Figure 1 is a sectional view of a block embodying the invention; Fig. 2 is a sectional view of a modification of Fig. 1; and Figs. 3 and 4 are sectional views of further modifications.

Referring to the drawings, A and B represent sheets of fabric, which are preferably sufficiently stiff to hold their shape during the molding process of making the block. This fabric is also preferably substantially impervious to plaster. By the term fabric, I mean to include paper, woven material, 10 felt, asbestos, strawboard, and any other fabric having the requisite qualities of stiffness and imperviousness above specified. At least one of the sheets of fabric A and B may be corrugated, as shown in this instance 15 the sheet A being corrugated, and the outer sheet B being flat and the exterior face of at least one of the sheets, as for instance, sheet A has adhering thereto a mass of hardened plastic material C. The plastic may 20 be plaster of Paris cement or the like, or any other suitable material preferably mixed with excelsior, cocoanut fiber or other binding or lightening material. For special uses asbestos fiber or powder, or magnesia may 25 be mixed with the plaster.

When the blocks are to be used in connection with refrigerating construction, both the plastic and the fabric should preferably be of waterproof material. An asphalt product mixed with powdered cork may be 60 taken as an example of a waterproof plastic. The fabric used may be waterproofed in any suitable manner as well understood.

In molding the block a mold of any suitable form may be used. A layer of plastic material C is then placed in the bottom of the mold. Preferably the two sheets of material A and B, one corrugated and the other flat are first fastened together in any suitable manner as by means of the upset eyes 65 E with a sheet of insulating material J in between and then this triple layer of fabric is placed in the mold on top of the plastic. The insulating layer J may be of any suitable 70 material, as for instance, felt or soft sheet of asbestos. The fabric will adhere to the plastic material as it sets. Another layer of plastic may be added if desired.

In all of the forms of the drawings, it is to be understood that the plastic material C may be on one side of the block as shown in Figs. 1, 2 and 3 or on both sides as shown in Fig. 4 and this arrangement of the plastic is understood to be interchangeable as desired. In Fig. 2 two corrugated sheets A 75 are shown separated by plastic material C'. Outside of the corrugated sheets are placed the sheets of insulating material J and the flat sheets B of fabric and plastic material C may be provided on one or both sides of 80 the block. In this instance the plastic forms the keys G to bind several of the parts together and fasteners E are provided to bind the outer sheet B to one corrugated sheet. In Fig. 3 the corrugated sheet A is placed 85 between two flat sheets B with a layer of insulating material underneath one sheet B and the sheets are fastened together as by means of the fasteners E. D represents the plastic shown on one side only of the block. In Fig. 4 two corrugated sheets A are shown 90 with an intermediate layer of insulating material J between the same and plastic material C on each side. In this case apertures F are provided in the three sheets and the plastic fills said apertures and forms the keys G to bind the parts together, as in Fig. 2. The layer J may be of any suitable 95 material, as specified.

In all of the forms shown in the draw-

ings, it will be seen that an air space or spaces are provided in the block and all of the forms of the block embody this principle.

5 I claim and desire to obtain by Letters Patent the following:

A composite insulating block comprising a corrugated waterproof sheet of stiffening fabric substantially impervious to plaster 10 and sufficiently stiff to hold its shape under pressure during the molding process of making the block, a layer of insulating material secured along one side of said corrugated sheet in direct contact with the ridges of 15 said corrugations, thereby forming air spaces between the corrugated sheet and the

layer of insulating material and an outer waterproof sheet of stiffening fabric substantially impervious to plaster applied to said insulating layer, the exterior face of at least one sheet of waterproof stiffening fabric having adherent thereto a mass of hardened waterproof plastic material mixed with binding or lightening material.

In testimony whereof I have signed this 25 specification in the presence of two subscribing witnesses, May 8, 1908.

JOHN E. HOWE.

Witnesses:

E. VAN ZANDT,
HERBERT G. OGDEN.
